PROCESS FOR EXTRACTING AND RECOVERING NICOTINE AND OTHER ORGANIC SUBSTANCES FROM TOBACCO

Lyell M. Rader, deceased, late of Burlington, N. C., by Jennie Campbell Rader, administratrix, Burlington, N. C., assignor to Chemical Extraction Corporation, Elkton, Ky., a corporation of Kentucky

Application July 15, 1938, Serial No. 219,423

6 Claims. (Cl. 260—291)

The invention relates to the processing of tobacco and more particularly has reference to a method for removing or extracting various organic compounds therefrom.

5 Numerous processes have been developed for the extraction of nicotine from tobacco. These have been designed primarily to produce a so-called denicotinized tobacco or for the purpose of obtaining nicotine for commercial uses. However, what ever may be their purpose, such extraction processes have resulted in costly products, and in so far as denicotinized tobacco is concerned an inferior one, due to their low extraction yield of nicotine and also their complicated procedure.

20 Chlorophyll, the green coloring matter of plants, has also been extracted. However, no processes for obtaining it from tobacco were known to the inventor prior to the invention herein. This substance, chlorophyll, which is extremely costly, has been rendered so by the small amount of the same which occurs in plants, its relatively low extraction yield and the complicated processes heretofore devised for obtaining it.

25 It is hence the major object of this invention to provide a method for extracting various organic compounds from tobacco.

An equally important object of the invention is 30 the provision of a method for the extraction of heterocyclic compounds from tobacco while preparing or leaving the same in condition for the subsequent extraction of other compounds and substances.

35 Another object of the invention is to provide for the complete destruction of the cellular structure of tobacco in a process for extracting various organic compounds therefrom.

Still another object of the invention is, in a 40 process for extracting organic compounds from tobacco, to destroy the cellular structure of the tobacco under treatment by subjecting it to a vacuum and steam treatment.

Yet another object of the invention is to devise 45 a method for extracting and recovering organic compounds from tobacco wherein gaseous ammonia is injected into the tobacco.

A further object of the invention is the provision of a method for extracting heterocyclic 50 compounds from tobacco wherein gaseous ammonia is injected into partially processed tobacco, the heterocyclic compounds being freed from the tobacco after the addition of the ammonia which combines with certain of the constituents remaining in the tobacco to form ammonia salts, and

dissolving the freed compounds in a suitable hydrocarbon oil so as to permit their recovery.

Still a further object of the invention is to provide an extraction process for recovering organic compounds from tobacco, wherein tobacco is subjected to a vacuum which is suddenly and partially broken by admitting steam into the closed tobacco containing compartment followed by the subsequent injection of gaseous ammonia and a light hydrocarbon oil therein, during all of which time the tobacco is subjected to violent agitation.

Yet a further object of the invention is the provision of a process for the extraction and recovering of nicotine and chlorophyll from tobacco.

A further object of the invention is to provide a completely denicotinized tobacco and a method for producing the same.

With these and other objects in view the invention consists in the method to be hereinafter set forth and claimed with the understanding that the steps thereof, the apparatus described for carrying them out, the reactants and solvents used as well as their quantities may be widely varied by those skilled in the art without departing from the spirit of the invention or the scope of the claims appended hereto.

Briefly the invention comprehends a process for extracting the heterocyclic constituents of tobacco, nicotine and chlorophyll, from the same while preparing or leaving the tobacco in a condition for further processing to obtain organic and inorganic products. One manner of practically effecting this concept is to draw a vacuum in the tobacco loaded container compartment of a suitable extractor mechanism. Steam is suddenly admitted into the compartment until the vacuum is half satisfied, after this gaseous ammonia is injected into the compartment. In most instances this will either wholly destroy the vacuum or raise a slight pressure in the compartment. A light hydrocarbon oil is now introduced, the tobacco having been subjected to violent agitation from a time prior to the drawing of the vacuum. After sufficient agitation it will be found that all of the nicotine and chlorophyll contained in the tobacco have been freed therefrom and have been taken up or dissolved in the oil while the ammonia has combined with some of the remaining constituents of the tobacco to form ammonia salts with them, as for example salts of certain of the polybasic acids such as oxalic, malic, and citric acids.

To recover the nicotine and chlorophyll the entire contents of the extractor are dumped into a

centrifuge and the oil is centrifuged off and sent to a clarifier. The tobacco in the centrifuge is then subjected to washing with clean or "wash" oil which is also centrifuged until the tobacco is 5 in as dry a state as possible, the removed oil also being sent to the clarifier. After clarification both the original and the wash oils are ready to have the nicotine and chlorophyll removed therefrom. Nicotine is extracted as a precipitated 10 nicotine sulphate by the addition of sulphuric acid and water to the oil while the chlorophyll is obtained, after the nicotine removal, by distillation of the oil and as a still deposit. Such distillation also recovers the oil employed in the 15 process for reuse.

The invention also contemplates further treatment of the tobacco left in the centrifuge, which despite washing and centrifuging still contain some oil, so called "center" oil. To the end of 20 removing this oil this denicotinized tobacco is placed in a second extractor where on the application of heat the oil is volatilized and sent to storage tank for reuse. There now remains an oil free denicotinized tobacco which may be used 25 as such or which is in condition for further processing to recover all of the valuable constituents remaining therein. Where such recovery is carried out the extraction results in the complete destruction of the tobacco to cellulose.

30 In order to make the invention more clearly understood, there is shown in the accompanying drawing, means for carrying the same into practical effect without limiting the improvements in their useful applications to the particular constructions which, for the purpose of explanation have been made the subject of illustration.

In the drawing:

The figure shows a flow sheet for a plant designed to carry out the process of this invention. 40 Throughout the drawing similar reference numerals refer to like parts and elements shown on the flow sheet.

In carrying out the invention tobacco in the raw state, either shredded or ground or in the 45 whole leaf or in stems is loaded onto conveyor 1 and by means of the elevator 2 is deposited into a storage bin 3 from whence it is introduced into one or more extractors 4.

The extractor or extractors 4 are connected 50 through a pipe line 5 to a proper means for drawing a vacuum within the tobacco containing compartment thereof and also have connected thereto a pipe line 6 through which steam and then ammonia may be injected therein from any suitable 55 sources of supply. In addition a pipe line 7, from an oil storage tank 8 leads into the extractors or extractor in order that oil from the storage tank may be introduced into each extractor in any well known manner.

60 Each extractor may be of any usual design. It is required however that the extractor or extractors be so constructed that a vacuum may be drawn in the tobacco containing compartment and also that they be able to withstand a slight 65 pressure above atmospheric in the compartment. Further each extractor must be constructed so as to provide for the violent agitation of the tobacco, as for example by rotation of the tobacco containing compartment and/or beating of the tobacco by paddles or blades mounted for rotation 70 therein.

75 After an extractor 4 is loaded, violent agitation of the tobacco is usually begun, and a vacuum is drawn in the tobacco compartment through the vacuum line 5. This vacuum is maintained for

a short period usually about two minutes, and is then half satisfied by injecting steam into the compartment through the line 6. Following this, anhydrous gaseous ammonia may be introduced into the extractor through the same line and then 5 a light hydrocarbon oil from the storage tank 8 is pumped or otherwise introduced into the tobacco mass in each extractor. Agitation is continued until upon analysis of the oil it is found that all of the nicotine displaced or freed from 10 the tobacco has been dissolved in the oil. Instead of beginning agitation of the tobacco as soon as the extractor is loaded, if desired, this step in the process may be delayed until after the addition of the oil to the extractor. 15

In explanation of the extraction steps of the process, it would appear that the vacuum and steam treatment causes the complete destruction of the cellular structure of the tobacco as distinguished from the partial destruction, or disruption, or modification of the cells thereof. With the treatment just described, it would seem that the ammonia, when added, frees or displaces the entire nicotine and chlorophyll content of the tobacco from the plant after which action it 20 chemically combines with certain of the constituents remaining in the tobacco by forming ammonia salts with them. The action occurring on the addition of the ammonia proceeds with such rapidity that it may well be that the nicotine and 25 chlorophyll are freed either simultaneously or separately. In any event, that the nicotine and the chlorophyll are freed is borne out by the fact that no traces of them are found in the tobacco after such processing. The freed nicotine and 30 chlorophyll are dissolved by the oil and it is from this solution that these substances are recovered.

Where the process is practiced with a tobacco having a 4% nicotine content a vacuum of about 40 26 inches drawn on the extractor has been found to work very satisfactory. The size or degree of the vacuum is primarily determined upon the fact that after half of it is satisfied by steam there must be sufficient remaining space in the extractor 45 to permit the introduction of ammonia gas, in slight excess of the theoretical amount needed to satisfy the nicotine content of the tobacco, without raising a pressure in the extractor which is much over normal. In the apparatus employed, where it is loaded with 500 pounds of tobacco having a 4% nicotine content the result of the injection of the steam and ammonia is to create a very slight pressure, less than a pound, in the extractor. This is usually the case in all 55 instances resulting from following the general guide for determining the amount of the vacuum. Actually whether the tobacco compartment is under a vacuum or a pressure after the steam and ammonia treatment is immaterial to the successful practice of the invention. The pressure is maintained as low as possible as a practical mechanical matter.

A vacuum of 26 inches has been mentioned. This is based on the treatment of 500 pounds of 65 tobacco having a 4% nicotine content in an extractor having a capacity of 87.132 cubic feet. It is important to note that the invention may be just as successfully practiced should a higher vacuum be drawn and for that matter even a somewhat lower one.

There has been found that in determining the amount of ammonia needed to cause complete extraction of nicotine and chlorophyll it is necessary to consider only the nicotine content of 75

the tobacco. Also, complete extraction success has been had using 0.5 pound of ammonia gas at N. T. P. per 100 pounds of tobacco with a nicotine content of 4% or in other words 0.5 pound of ammonia for every 4 pounds of nicotine is needed. To give this in cubic feet of gas at N. T. P., 10.518 cubic feet of ammonia per 100 pounds or 52.59 cubic feet of ammonia per 500 pounds of 4% nicotine tobacco is necessary. In practice ammonia in slight excess of the theoretical amount needed to satisfy the nicotine content of the tobacco is employed. The figures given in the foregoing are working quantities and all include this excess.

As already mentioned a solvent is used for extracting the replaced nicotine and chlorophyll. Any light hydrocarbon oil similar to kerosene is employed for this purpose. For example, deodorized kerosene and hydrogenated naphtha have been found to work effectively. With a 4% nicotine tobacco 3 pounds of oil to 1 pound of tobacco are injected into the extractor. Where a tobacco with a lower nicotine content is processed a less amount of oil per pound of tobacco may be used although it should be noted that the only effect on the invention of the employment of oil in excess of that needed is to increase the processing costs of the extracted products.

Violent agitation of the tobacco has been described. The purpose of this is to allow the steam, ammonia, and oil to be quickly distributed throughout the tobacco. Also it hastens the dissolving of the nicotine and the chlorophyll by the oil and generally speeds up the time cycle in plant operation. Agitation is continuous for from 15 minutes or even less to about 30 minutes. This time is determined by the amount of tobacco being treated, its nicotine content and the physical form and condition of the tobacco, as for example its age and curing.

In any event the agitation period is easily and quickly ascertained by analysis of the solvent oil until it is found that the nicotine content of the oil equals the nicotine content of the tobacco undergoing processing, upon which, agitation is arrested. However, no harm will be done to the tobacco should agitation continue longer than is actually necessary.

After sufficient agitation, the tobacco and oil is now dumped into a centrifuge 9 from tobacco bin 10 where it has been conveyed from each extractor 4 by means of the conveyor 11 and elevator 12. Here the entire mass is centrifuged at a very high speed to the end of removing from the tobacco as much of the solvent oil as is possible. Oil removed by this step in the process is sent to a centrifugal separator or clarifier 14, which will be presently mentioned. With the tobacco in the centrifuge in as dry a state as possible, 1 pound of clean or wash oil per pound of tobacco is introduced therein from the storage tank 8 through the oil line 13, the entire centrifuging step just outlined being repeated and the wash oil being finally removed to the clarifier.

As mentioned the original oil used as a solvent and also the wash oil, both of which contain nicotine and chlorophyll, are passed through a clarifier 14. These oils are introduced therein by way of the oil line 15 which drains the centrifuge into an oil receiving tank 16 from whence they are pumped through line 17 to a surge bin 18 connected directly to the clarifier 14. From the clarifier the oil is removed to a mother li-

uor tank 19 through exhaust line 20 connected to the exhaust or outlet end of the clarifier. The clarification here as well as the centrifuging mentioned is done at very high speed. Its purpose is to remove tobacco dust and tobacco particles and also any pectin, obtained from the tobacco, which might be in the oil.

Both oils, now in the mother liquor tank are ready to have the nicotine and chlorophyll removed from them. This is accomplished by feeding the oil through pipe line 21 into separating tanks 22 where the nicotine is precipitated as nicotine sulphate by the addition of sulphuric acid and water to the oil from the acid tank 23 which is supplied by the acid egg 24. Generally sufficient acid is added to produce a 40% nicotine sulphate, the usual commercial grade. However in practice it is sometimes found advisable to extract a weaker sulphate and then subsequently concentrate it by adding pure nicotine thereto.

The separating or precipitate tanks can be provided with agitators so that if desired the oil can be agitated during the addition of the acid and water thereto. This is for the purpose of thoroughly dispersing the acid and water through the oil.

The oil now remaining contains only chlorophyll in solution. This oil and the nicotine precipitate are removed from the precipitate tanks 30 and are passed through line 25 to a clarifier 26. Here on clarification the nicotine sulphate is removed as shown at 27 while the clarified oil is sent through line 28 to a recovery tank 29 which is connected through a pipe line 30 to a recovery still 31. The nicotine sulphate may be further processed for purification if desired or pure nicotine may be extracted therefrom in any well known manner.

In the recovery still the oil is subjected to any usual distillation process so that it may be recovered for reuse. The purified oil is then stored in storage tank 8, connected to the still by line 32, for this purpose. However, there remains in the still a crude chlorophyll which of course is one of the compounds this invention is designed to extract from the tobacco. The crude chlorophyll is now removed from the still and is ready for suitable refining.

Despite centrifuging after washing with clean oil there still remains in the tobacco in the centrifuge 9 a small amount of the wash oil. This is the so called "center oil." It is desired to obtain an oil free denicotinized tobacco and to this end the treated tobacco in the centrifuge is transported to conveyor 33 where it is carried by elevator 34 to storage bin 35 for loading into one or more extractors 36 where the oil is removed by volatilization.

For applying heat to the tobacco, in order to volatilize the oil, each extractor 36 is jacketed and has the jacket connected to a steam line 37 from a hot water tank 38 which is also heated by steam. If desired steam may also be injected directly into the tobacco in the container compartment of the extractor, although this is not necessary. Also instead of heating the jackets with steam, boiling water from the hot water tank may be employed for this purpose, but this practice is not preferred. The volatilized oil is taken off from the extractors through line 39 and sent to a separator tank 40 where any water that may be in the oil is removed and discarded through the outlet line 41 and the oil itself is sent direct to the storage tank 8 through line 75

42. It will be found that this volatilization step leaves a completely oil free denicotinized tobacco. Since this oil is the remainder of the clean wash oil left in the tobacco it will not need to be recovered by distillation before it may again be used.

There is during the carrying out of the entire process, and despite oil recovery, a mechanical loss of about 1% of the amount of the original oil used. To keep this loss as low as possible all equipment is provided with fume proof gasket joints. For the purpose of filling the storage tanks, a supply line 43 connects the tank to any suitable source of oil supply so that fresh oil may be discharged into the tank.

There now remains an oil free denicotinized tobacco, which may be removed for use as such, or is ready for further processing in order to free other constituents therefrom. This latter step, which does not form part of this invention, may be accomplished by injecting steam and/or boiling water into the extractor while the tobacco is violently agitated.

The value of the process may be realized when it is considered that the remaining tobacco on analysis will be found to be completely denicotinized. From this fact a high extraction yield should be expected. That such is the case is clearly illustrated when it is pointed out that over many recorded runs in a pilot or test plant consistently well over 3½% of nicotine has been recovered from a tobacco (Kentucky tobacco) averaging a total content of 4% of nicotine or in other terms a recovery yield of 87½% of the total nicotine content of the tobacco which total content has been entirely extracted from the tobacco. The size of this yield will be appreciated when it is considered that the runs were made with a pilot plant where there are many mechanical losses. While relatively high recovery yields for nicotine have been recorded in the past it should be noted that for yield comparison they have been obtained by methods possessing the disadvantage of failing to extract all of the nicotine and invariably leave the tobacco with at least a 1% nicotine content.

Recovery yields from the pilot plant of approximately 95% have been obtained and with commercial practice of the invention over 98% of the nicotine should be recovered. It should be noted that an analysis of the solvent oil after precipitation and separation of the nicotine will show but the barest of a trace of nicotine remaining therein. However, whatever recovery yield is obtained, it should be constantly kept in mind that the invention is designed to extract all of the nicotine from tobacco for the purpose of obtaining an inexpensive product and for preparing the tobacco for the extraction of its other constituents if such latter is desired.

At the present time but comparatively little is known about chlorophyll. At least, so far as the inventor was aware no attempts had been made to extract it from tobacco. The chlorophyll content of any plant is of course relatively small and in the case of tobacco is less than that of the nicotine. Moreover the chlorophyll content of tobacco will vary with the condition of the tobacco as for example its age, kind and length of curing, and drying and other like factors. Even with pilot plant operation it has been possible to remove all of the chlorophyll from the tobacco treated, as is the case of the nicotine. This compound is in effect a by-product of the main nicotine extraction process. In the pilot

plant operation 2 to 3 pounds of crude chlorophyll per 100 pounds of Kentucky tobacco, which as pointed out will average a nicotine content of 4%, has been obtained.

From the foregoing it will be appreciated that there has been invented a novel process for extracting nicotine and chlorophyll from tobacco and one which can be performed cheaply and simply. The low cost of the extracted products is of course caused by the simplicity of the process as well as its effectiveness which results in a high yield and leaves the tobacco in a condition for further processing, to the end of removing all of the valuable constituents remaining therein.

Also important to note is the fact that should any step of the process be carried out in excess, as for example regarding the elements of time and amount or quantity, no harm is caused to the tobacco nor is the extraction yield of the products to be recovered effected.

While the preferred embodiment of the invention has been shown and described, it is to be understood that the invention is not confined to the specific method steps and the details of the construction of the apparatus for carrying out the method herein set forth, by way of illustration, as it is apparent that many changes and variations may be made therein, by those skilled in the art, without departing from the spirit of the invention, or exceeding the scope of the appended claims.

There is claimed:

1. In a process for extracting nicotine and chlorophyll from tobacco the steps of, subjecting a processing compartment containing tobacco to a vacuum of about twenty-six inches within the limit substantially as set forth, partially satisfying the vacuum with steam to an extent that by thereupon admitting sufficient gaseous ammonia at N. T. P. into the compartment to theoretically replace the nicotine content of the tobacco being processed the remaining vacuum will be satisfied, the tobacco at no time subjected to a temperature sufficient to destroy the chlorophyll.

2. In a process for extracting nicotine and chlorophyll from tobacco the steps of, subjecting a processing compartment containing tobacco to a vacuum of about twenty-six inches within the limit substantially as set forth, partially satisfying the vacuum with steam to an extent that by thereupon admitting sufficient gaseous ammonia at N. T. P. into the compartment to theoretically replace the nicotine content of the tobacco being processed the remaining vacuum will be satisfied, such treatment of the tobacco freeing the nicotine and chlorophyll therefrom, and then injecting a solvent oil into the compartment to dissolve the freed compounds, the tobacco at no time subjected to a temperature sufficient to destroy the chlorophyll.

3. In a process for extracting nicotine and chlorophyll from tobacco the steps of, subjecting a processing compartment containing tobacco to a vacuum of about twenty-six inches within the limit substantially as set forth, partially satisfying the vacuum with steam to an extent that by thereupon admitting sufficient gaseous ammonia at N. T. P. into the compartment to theoretically replace the nicotine content of the tobacco being processed the remaining vacuum will be satisfied, such treatment of the tobacco freeing the nicotine and chlorophyll therefrom, and then injecting a solvent oil into the compartment to dissolve the freed compounds, the tobacco be-

ing subjected to violent agitation during treatment, the tobacco at no time subjected to a temperature sufficient to destroy the chlorophyll.

4. In a process for extracting nicotine and chlorophyll from tobacco the steps of, subjecting a processing compartment containing tobacco to a vacuum of about twenty-six inches within the limit substantially as set forth, maintaining the tobacco under the vacuum drawn for a relatively short time, then partially satisfying the vacuum with steam to an extent that by thereupon admitting sufficient gaseous ammonia at N. T. P. into the compartment to theoretically replace the nicotine content of the tobacco being processed the remaining vacuum will be satisfied, the tobacco at no time subjected to a temperature sufficient to destroy the chlorophyll.

5. In a process for extracting nicotine and chlorophyll from tobacco the steps of, subjecting a processing compartment containing tobacco to a vacuum of about twenty-six inches within the limit substantially as set forth, maintaining the tobacco under the vacuum drawn for approximately two minutes, then partially satisfying the vacuum with steam to an extent that by thereupon admitting sufficient gaseous ammonia at N. T. P. into the compartment to theoretically

replace the nicotine content of the tobacco being processed the remaining vacuum will be satisfied, the tobacco at no time subjected to a temperature sufficient to destroy the chlorophyll.

6. In a process for extracting nicotine and chlorophyll from tobacco freeing these compounds from tobacco by subjecting a processing compartment containing tobacco to a vacuum of about twenty-six inches within the limit substantially as set forth, maintaining the vacuum for approximately two minutes, then partially satisfying the vacuum with steam to an extent that by thereupon admitting sufficient gaseous ammonia at N. T. P. into the compartment to theoretically replace the nicotine content of the tobacco being processed the remaining vacuum will be satisfied, and introducing a solvent hydrocarbon oil into the compartment to dissolve the freed nicotine and chlorophyll, the tobacco being violently agitated during this treatment and until all of the nicotine is in solution, and the tobacco at no time subjected to a temperature sufficient to destroy the chlorophyll.
